APPARATUS FOR WASHING PULP

Edward T. Street, Downingtown, Pa., assignor to
Downingtown Manufacturing Company, Down-
ingtown, Pa., a corporation of Pennsylvania

Application May 19, 1938, Serial No. 208,929

3 Claims. (Cl. 68—22)

In the art of manufacture of paper, card-
board, wallboard and the like from wood fiber
it is customary to first reduce the wood which
is used as raw material to chips by any one
of several possible methods. These chips are
then placed in a digester, together with a strong
solution of chemicals in water, the digester being
then sealed and its contents being "cooked" for
a substantial length of time under pressure.
When the process of digestion has advanced to
the desired extent, the digester is unsealed and
its pulp-like contents removed for further proc-
essing. The pulp stock delivered by the digester
includes all of the chemicals originally inserted
into the digester for the purpose of breaking
down the chips and it is then necessary to sepa-
rate the pulp from such chemicals in order that
the pulp itself may be substantially freed of the
digesting chemicals before it is made into paper,
fiber board or the like and also to recover the
digesting chemicals for reuse. The chemicals
used are costly and inasmuch as large quantities
must necessarily be employed in large scale oper-
ations it is essential, if the process is to be eco-
nomically conducted, that a very large proportion
of these chemicals be recovered. These facts
have been long appreciated by workers in the
art and numerous suggestions have heretofore
been made looking toward the increased recov-
ery of the chemicals made use of in order that
the cost of operation of the process as a whole
may be minimized. Where large quantities of
water must necessarily be used to thoroughly
wash the chemicals from the digested pulp the
chemical solution becomes greatly diluted and,
before it can be reused, the large excess of water
must be driven off. The cost of operation of
the process as a whole bears a close relationship
to the efficiency of the process used for the re-
covery of the digesting chemicals and in some
cases it is actually found to be less costly to waste
a substantial proportion of the chemicals used
than it is to recover these chemicals from a
very dilute solution thereof. In other processes
the chemicals are recovered in part and dis-
carded in part, the object being in every case
to recover those chemicals which can be actual-
ly recovered with economy and to discard those
which may not be economically recovered.

The present invention contemplates the pro-
vision of an improved apparatus for, and method
of, washing the fibrous pulp delivered by a di-
gestor so that this pulp is substantially freed
of all of the chemicals which were used in the
digesting process, this washing operation being

carried out in such a way that all portions of
the pulp delivered are subjected to the same
washing action, a minimum quantity of water,
however, being used so that the solution of di-
gesting chemicals is diluted only to an extent
appreciably less than heretofore realized with
known processes. As a result reconcentration
of the chemical solution in the well-known re-
covery apparatus may be effected at small ex-
pense and the cost of the operation as a whole
minimized.

I have discovered that it is possible to most
economically and thoroughly wash freshly di-
gested pulp if the pulp be reduced to the form
15 of a uniform and homogeneous layer or board
and the washing operation be effected by pass-
ing the washing liquid through the board. Each
fiber of which the board is composed, therefore,
is subjected to the direct flow of the washing
liquid and all fibers are washed to the same ex-
tent by such liquid. In other words, after the
formation of a homogeneous or uniform board
of matted fiber, washing liquid may be passed
20 therethrough in such manner that the rate of
flow through all portions of the board is the
same, channeling, or more rapid flow of wash
liquid through one portion of the pulp mass than
through another portion, being avoided. All
known processes heretofore or at present em-
ployed, involving the passage of wash liquid
25 through a pulp body, have required the use of
excessive quantities of the washing liquid due
to the tendency of such liquid to follow the line
of least resistance through the pulp mass. This
necessitates the use of excessive quantities of
30 water if all parts of the pulp mass are to be
adequately washed. However, by reducing the
pulp mass to the form of a board which is uni-
form in character, and offers equal resistance
35 to the passage of the washing liquid over all
areas thereof, this tendency to channel is wholly
obviated and thorough washing is obtained by
40 the use of the smallest possible quantity of wash-
ing liquid.

45 The improved process also includes as an im-
portant step a fiber pressing operation inter-
posed between the board forming and washing
operations. By causing the fiber to be deposited
50 in a layer of substantially uniform thickness it
is made easily possible to apply heavy compres-
sive forces thereto for the purpose of expelling
a large proportion of its contained liquid (com-
monly called "black liquor") prior to the wash-
ing operation, thus removing from the fiber much
55 of the chemical bearing liquid before it is di-

luted with wash liquid. Thus, by passing the freshly formed fibrous board between pressure rollers from 60% to 65%, or even more, of its contained liquid may be mechanically removed, leaving in the board only a fraction of the chemical bearing liquid to be removed by subsequent washing operations. After the pressing step has been performed only about one and one half (1½) pounds of liquid per pound of fiber remains, whereas in prior processes seven or eight pounds of liquid per pound of fiber or 85% to 90% of the chemical bearing liquid must be removed by washing, and is thereby greatly diluted. The great economy of the process is, in this respect, apparent.

While the improved method may be practiced with the aid of apparatus which may vary widely in design and construction, the freshly digested pulp may advantageously be introduced into the forming chamber of an apparatus of the type disclosed in my prior Patent 1,927,378 and that the board to be subsequently subjected to the washing operation be formed by deposition of fiber from the body of pulp stock onto a foraminous member. When such a board forming apparatus is employed the process may be made continuous, i. e., the pulp stock from one or more digesters may be introduced into the board forming chamber at a known rate, a board of the desired thickness formed by deposition at a controlled rate so that its thickness may be as desired and removed from the chamber at the rate at which it is formed, to be subjected, after removal, to the stated pressing and washing operations. By preference, the process is practiced in an apparatus embodying endless upper and lower complementary foraminous belts or forming wires, the board being formed by deposition of the fiber upon the upper reach of the lower belt and the lower reach of the upper belt resting upon the upper surface of the formed board and comprising a confining means which prevents displacement of the fibers during the time that the board is undergoing pressure and washing liquid is being passed through the same.

While I refer to a washing operation performed upon a "board" it will be understood that, while the pulp has been reduced to board form, this does not mean that the board has such strength that it may be used for any purpose. On the other hand the "board" comprises interlaced fibers, includes no binding material and in reality is a flat, pulpy mass, and of uniform thickness and homogeneous character throughout. In this state it offers no great resistance to the passage of liquid therethrough and washing operations may be easily and conveniently carried out by maintaining a body of washing fluid upon its upper surface, movement of the water through the board being effected by maintaining the body of washing liquid under a sufficiently high static pressure or by applying suction to the under-surface of the board, or by utilizing both the static pressure of the wash liquid and a suction device to effect such flow. Preferably the washing operation is accomplished by means of a plurality of washing devices by which the board is successively passed so that it may be said to be repeatedly washed. Advantageously also the board after each washing operation is subjected to the action of pressure rollers and by means of which fluid contained therein is largely pressed out. The pressure applied to the board by the rollers likewise distributes the wash liquid through the body of the board and to a certain extent

causes the liquid to flow through the fibers longitudinally of the board in a direction opposite to that in which the board is moving. This promotes thorough washing.

When the washing operation is accomplished in a series of stages the wash fluid which is used in the last stage may advantageously be fresh water and the board, after it passes this last washing station, is substantially free of chemicals. The water which is passed through the board in the last washing station, which of course contains, after such passage, a quantity of chemicals in solution, is collected, elevated by means of a pump, and used as the washing liquid at the preceding or next to last washing station, and where there are three or more washing stations a given quantity of wash liquid will be passed through the board three or more times, being advanced from station to station in a direction opposite to that in which the board is moving. Any number of washing operations may be carried out in this way and the number of times that the board will be subjected to such washing operations will depend upon the chemicals used in the digestive process, the thickness of the board, the speed at which the board is moving, the character of the fibers, and upon other factors. Where suction boxes are employed the rate of flow of wash liquid may be controlled by regulating carefully the degree of vacuum which exists in the suction boxes.

The liquid from the last washing operation, which may have been passed several times through the board, is rich in the chemicals removed from the board and is passed on to any well-known recovery apparatus whereby excess water is driven off. The invention contemplates a number of novel and improved features, both in the method and apparatus, not heretofore referred to, but which will be hereinafter described in detail and pointed out in the appended claims. Two typical forms of apparatus by which the process may be carried out are illustrated in the accompanying drawings by way of example, such apparatus being rather diagrammatically shown.

In the drawings:

Figure 1 shows partially in longitudinal vertical section, and partially in side elevation, one form of board forming and board washing apparatus, many of the conventional features of such apparatus having been omitted in order that the more essential features may be more clearly perceived;

Figure 2 is a vertical section, taken longitudinally of the machine, through a pair of pressure rollers and the adjacent means for passing wash liquid through the board;

Figure 3 is a section on line 3—3 of Figure 2;

Figure 4 is a view, generally similar to Figure 1, of a form of apparatus for use in the practice of the novel method, certain elements of this apparatus differing in form and arrangement from the corresponding elements shown in the apparatus illustrated in Figure 1; and

Figure 5 is a section on line 5—5 of Figure 4.

The board forming chamber is indicated generally at 10 and a body of unwashed pulp stock therein at 11. The chamber 10 is rectangular in transverse vertical section and generally triangular in longitudinal vertical section, as shown. The bottom of the chamber comprises the upper horizontal reach of a foraminous belt or wire indicated at 12, this reach of belt being supported upon rollers 13 mounted in the frame of the machine and moving, when the machine is in

operation, in the direction indicated by the arrow A. While any given area of the forming wire 12 is disposed beneath the stationary portion of the forming chamber 10 the pulp stock liquid passes downwardly through the same and the fibers dispersed in this liquid are deposited upon the upper surface of the belt, a board or mat being thus gradually built up on each such section of the wire as it moves from left to right, the speed of the wire being so controlled that the board which issues from the discharge end of the forming chamber is of the desired thickness. Novelty is not claimed broadly herein either for the method of fiber deposition in the formation of the board, which is substantially the same as that disclosed in Patent 1,927,359, issued September 19, 1933, to Jacob Edge, or for the apparatus employed, which may advantageously be of the general type disclosed in the aforementioned patent to Jacob Edge or in my prior Patent 1,927,378, elsewhere herein referred to.

There is diagrammatically illustrated at 14 a tank or receptacle for digested but unwashed pulp stock which has been refined or both refined and screened to render it suitable for introduction into the forming chamber. The discharge pipe 15 from tank 14 leads to the intake of a variable speed pump 16 which may be of the centrifugal type, this pump discharging into conduit 17 which in turn opens into a mixing chamber 10' at the extreme end of the forming chamber 10. By regulating the speed of pump 16 the rate of delivery of unwashed pulp stock to the mixing chamber may be accurately controlled and the level of the upper surface of the pulp stock in the forming chamber kept at the desired height. Another advantage of utilizing a pump of this type is that it will deliver the pulp stock into the forming chamber without the creation of foam. The stream of unwashed pulp stock entering the extreme end of the mixing chamber encounters a series of baffles 10² and it is while the pulp stock is passing through the tortuous passage thus defined that it is mixed with a diluting liquid for the purpose of more widely dispersing the fibrous elements in the body of liquid in order that the subsequent deposition of the fibers on the forming wire or belt may proceed uniformly over the entire area of that portion of the belt which comprises the movable bottom of the forming chamber, and a uniform board be produced. Thus the liquid which passes through the forming wire or belt 12 at the bottom of the forming chamber is collected in a pan 20, from which pan it flows downwardly through a short vertical conduit 21 into a liquid receiving tank 22. From this tank it is drawn by means of a variable speed centrifugal pump 23 and passed through a conduit 24 of large cross-section at a relatively low rate of speed to be eventually discharged upwardly through an aperture in the bottom of the mixing chamber at a point adjacent the discharge end of the conduit 17. Hence the stream of unwashed pulp stock introduced into the mixing chamber is met shortly after its entry by the upflowing stream of fiber-free diluting liquid and the two streams are intimately intermingled in passing through the tortuous conduit defined by the baffles 10² and the walls of the chamber, and before entering the forming chamber.

As the formed board leaves the forming chamber it passes beneath a series of primary press rolls indicated at 26 and at this point the upper forming wire or belt, which is indicated at 27, comes into contact with its upper surface, the belt

27 being driven at the same speed as that at which the lower belt 12 is driven, and in the direction of the arrow B. Thereafter the board is retained between parallel reaches of the upper and lower forming wires or belts until it is discharged by the apparatus, the board at the discharge end of the machine being indicated at 28. Four pairs of horizontally disposed main press rolls are shown, the rolls of the first pair being indicated at 29 and 30, and the rolls of the remaining pairs being indicated at 31 and 32, 33 and 34 and 35 and 36 respectively. The fibrous board and its associated confining wires pass successively between the pairs of rolls and at each roll pass are subjected to pressure, the degree or extent of which may be varied as desired by means of weights or adjustable springs. In the case of the apparatus shown at least the upper rolls 29, 31, 33 and 35 are vertically movable and any conventional weighting or resilient means may be employed to thrust the rolls downwardly.

A plurality of wash liquid retaining boxes are shown, these boxes being indicated at 38, 39 and 40 respectively and being positioned intermediate the upper main press rolls, one box between each two rolls. Vacuum chambers are indicated at 41, 42 and 43, one such vacuum chamber underlying each wash liquid box, the board 28 and its confining wires, of course, passing between each wash liquid box and the vacuum chamber underlying the same. The several wash boxes 38, 39 and 40 are supported upon the upper main press rolls so that these boxes will be raised and lowered simultaneously with the associated press rolls and hence will maintain a constant relationship to the lower reach of the upper forming wire 27 at all times. The means for supporting the wash liquid boxes from the press rolls includes longitudinally extending supporting rods or bars 45 and 46 each such bar having upwardly curved portions or loops which overlie and rest upon the several roll necks so that the supporting bars 45 and 46 are actually carried by the necks of the upper main press rolls. Each wash box is provided with two bracket members at each end, these brackets being indicated at 47 and 48 respectively and each bracket having an extension overlying the adjacent longitudinally extending bar. Adjusting screws 49 and 50 extend downwardly through and have threaded engagement with the cylindrical threaded walls of apertures formed in the overhanging portions of brackets 47 and 48, the lower ends of these screws resting upon the box supporting bars 45 and 46 respectively. By means of these adjusting screws the exact position of the lower edge of each wash box relatively to the supporting bars 45 and 46 may be determined and hence the positions of these lower edges accurately located with respect to the axes of the upper main press rolls.

Each wash liquid box is preferably provided at its lower edge with a sealing member 52 which bears upon the upper forming wire 27 in order that a body of wash liquid of substantial depth may be maintained in the box without causing excessive leakage between the lower edges of the box and the wire and board beneath the same. These sealing members may be formed in various ways and of various materials. The vacuum chamber associated with each wash liquid box includes a foraminous top, one such top being indicated at 54 in Figures 2 and 3, the upper surface of the top member 54 being flat so that the upper reach of the lower forming wire may slide freely thereacross. It will be perceived from Fig-

ures 2 and 3 that, while the suction box has substantially the same length as the superposed wash liquid box, measured transversely of the machine, it is substantially longer, measured longitudinally of the machine, its upper member 54 extending into close proximity to the adjacent roll pass. Hence when a partial vacuum is created within the suction box suction is applied over a greater area of the fiber board than that which is covered by the associated wash liquid box and the suction created will not only draw wash liquid from the box, through the intermediate board, but will also draw directly through the board the body of liquid which is developed upon its upper surface by reason of the pressing action of the adjacent pair of main press rolls, such a quantity of expressed liquid being indicated at 55 in Figure 2. This construction is such that foaming of the liquid, as it is drawn from and through the board, is minimized.

Clean wash water is introduced into the last of the wash liquid boxes, i. e., into box 40, through a conduit 56 and if desired steam may be likewise introduced into the stream of wash water through a conduit 57 for the purpose of heating the water, water and steam valves being indicated at 58 and 57' respectively. Water passing from wash liquid box 40 through the board 28 is collected in the vacuum chamber 43 and escapes from this chamber through a pipe 59 into a downtime 60 leading to a separating chamber 61. The downtime 60 has a portion extending upwardly above the conduit 59 and the upper end of this upward extension communicates with a horizontally disposed pipe or manifold 62 which is in constant communication with a vacuum pump or the like. A pressure gauge is indicated at 63, and a valve at 64 by means of which the degree of vacuum existing in the pipe 60 below this valve, and hence in the separating chamber 61, and in the vacuum box 43, may be controlled. By regulating the degree of vacuum in the vacuum box the rate of flow of wash liquid through the moving board at this point may be controlled. A liquid circulating pump is indicated at 66, this pump working against the vacuum existing in separating chamber 61 and serving to withdraw liquid from this chamber. The outlet of pump 66 communicates with a vertically extending pipe or conduit 67 having a horizontal branch 68 terminating in a downwardly extending end portion 69 positioned directly above the next adjacent wash liquid box 39. By similar means the wash liquid which is collected in the vacuum box 42 is delivered to the wash liquid box 38. The wash liquid collected in the vacuum chamber 41 is, however, pumped to the recovery system, the pipe 70 leading to the recovery system which may be employed. A vacuum box 72, positioned anteriorly to the first pair of main press rolls 29 and 30, serves to draw liquid from the board, no wash water being applied to the upper surfaces of the board at this point, and as this liquid is very rich in chemicals, being undiluted with wash liquid, it is separately delivered to the recovery system by means of separating chamber 73, pump 74 and delivery conduit 75. Vacuum chamber 72 is connected to the manifold 62 and provided with the usual means for regulating the degree of vacuum therein.

The apparatus illustrated in Figures 4 and 5 is, in major respects, similar to that shown in Figure 1, but instead of a forming chamber of the type shown in that figure it includes a simple

means for flowing a stream of pulp stock horizontally onto the forming wire and elements in the nature of side boards or deckels for laterally confining this stream on the wire until all of its free liquid has passed through the wire. Also, in this apparatus water columns are employed to create sub-atmospheric pressures in the suction boxes instead of vacuum pumps directly connected to water and gas separating chambers, such as used in the apparatus first described.

Here unwashed pulp stock from tank 80 is forced by pump 81 into a mixing or dilution box 82 where it meets the stream of black liquor issuing from pipe 83 and the intermingled streams, after passing baffles 84 and 85, pass over the curved forewall 86 of the box 82 directly onto the forming wire 87. The liquid carrier for the fibers passes through the wire before the stream has travelled, on the wire, more than a few feet, leaving a liquid-soaked fibrous mat or board on the upper surface of the wire. The fiber bearing liquid is thus under negligible static head when flowed onto the wire but by regulating the rate of flow of pulp stock and the speed of movement of the wire the rate of fiber deposition can be closely controlled and very satisfactory results obtained. The side boards or deckels 82' prevent the fiber carrying liquid from flowing laterally from the wire 87.

30 The board compressing and washing means are substantially as before except in that the conduits 88, 89 and 90 leading downwardly from the suction boxes 91, 92 and 93 are relatively long and are open at their lower ends to discharge 35 into liquid collecting water seal boxes 94, 95 and 96. Pumps 97, 98 and 99 draw liquid from these boxes, respectively, but these pumps do not work against a vacuum nor draw from chambers containing both gas and liquid, so that danger of 40 foaming is minimized. In operation the level of the water columns in pipes 88, 89 and 90 will be at such height above the seal boxes 94, 95 and 96, respectively, that each water column will 45 balance the vacuum and, as additional water collects in each pipe it will displace some of the water previously collected, which will then flow into the seal box and be eventually removed by the associated pump. The additional suction chamber 100 is likewise provided with an extended downtime pipe 101, water seal box 102, and pump 103.

In practicing the process upon either form of apparatus both pulp stock liquid and wash water are maintained at relatively high temperatures for best results. Thus I prefer to have the temperature of the fiber carrying liquid in the neighborhood of 190° F. when it is passed onto the forming wire and the wash liquid is preferably maintained at a temperature of between 180° F. and 200° F.

60 These relatively high temperatures are maintained in order to keep the black liquor in freely flowing condition. The viscosity of this liquid increases as its temperature falls and even at room temperatures it may be too viscous. Also the wash water dilutes the black liquor more rapidly at high temperatures, which is helpful in washing.

Having thus described the invention, what is claimed as new and desired to be secured by Letters Patent is:

1. Pulp washing apparatus comprising in combination, an elongated foraminous belt, stationary means above the belt for continuously depositing fiber thereon at a uniform rate, mecha-

nism for advancing the belt at uniform speed past said means so that a continuous fibrous board, homogeneous and uniform in thickness, is in constant course of formation on said belt, a second foraminous belt positioned above the first, a connection between said mechanism and said second belt whereby said second belt is driven at the same linear velocity as the first belt, means constraining said belts to move along predetermined paths, causing them first to gradually approach each other to place the newly formed board under light but gradually increasing pressure and to thereafter closely confine the board during its travel to a point of discharge, where the belts again separate, said means including cooperating lower and upper pressure rollers engaging the respective belts and coacting to subject the previously lightly compacted board to heavy pressure as it advances to remove therefrom the greater portion of its contained liquid, and means to continuously wash the board after such compression, said last mentioned means including a box having an open bottom for maintaining a substantial body of wash water continuously in full contact with a large area of the upper foraminous belt.

2. Pulp washing apparatus comprising in combination, an elongated foraminous belt, stationary means above the belt for continuously depositing fiber thereon at a uniform rate, mechanism for advancing the belt at uniform speed past said means so that a continuous fibrous board, homogeneous and uniform in thickness, is in constant course of formation on said belt, a second foraminous belt positioned above the first, a connection between said mechanism and said second belt whereby said second belt is driven at the same linear velocity as the first belt, means constraining said belts to move along predetermined paths, causing them first to gradually approach each other to place the newly formed board under light but gradually increasing pressure and to thereafter closely confine the board during its travel to a point of discharge, where the belts again separate, said means including

horizontally spaced upper rollers for successively engaging the upper foraminous belt and correspondingly spaced rollers for engaging the lower belt and coacting with said upper rollers, respectively, to successively subject all areas of the moving board to heavy pressure, and means intermediate, and supported by, said spaced upper rollers for maintaining a substantial body of wash water continuously in full contact with a large area of the upper foraminous belt.

3. Pulp washing apparatus comprising in combination, an elongated foraminous belt, stationary means above the belt for continuously depositing fiber thereon at a uniform rate, mechanism for advancing the belt at uniform speed past said means so that a continuous fibrous board, homogeneous and uniform in thickness, is in constant course of formation on said belt, a second foraminous belt positioned above the first, a connection between said mechanism and said second belt whereby said second belt is driven at the same linear velocity as the first belt, means constraining said belts to move along predetermined paths, causing them first to gradually approach each other to place the newly formed board under light but gradually increasing pressure and to thereafter closely confine the board during its travel to a point of discharge, where the belts again separate, said means including
- 15 horizontally spaced upper rollers for successively engaging the upper foraminous belt and correspondingly spaced rollers for engaging the lower belt and coacting with said upper rollers, respectively, to successively subject all areas of the moving board to heavy pressure, and means intermediate, and supported by, said spaced upper rollers for maintaining a substantial body of wash water continuously in full contact with a large area of the upper foraminous belt.
- 20 first, a connection between said mechanism and said second belt whereby said second belt is driven at the same linear velocity as the first belt, means constraining said belts to move along predetermined paths, causing them first to gradually approach each other to place the newly formed board under light but gradually increasing pressure and to thereafter closely confine the board during its travel to a point of discharge, where the belts again separate, said means including
- 25 horizontally spaced upper rollers for successively engaging the upper foraminous belt and correspondingly spaced rollers for engaging the lower belt and coacting with said upper rollers, respectively, to successively subject all areas of the moving board to heavy pressure, and means intermediate, and supported by, said spaced upper rollers for maintaining a substantial body of wash water continuously in full contact with a large area of the upper foraminous belt.
- 30 horizontally spaced upper rollers for successively engaging the upper foraminous belt and correspondingly spaced rollers for engaging the lower belt and coacting with said upper rollers, respectively, to successively subject all areas of the moving board to heavy pressure, and means intermediate, and supported by, said spaced upper rollers for maintaining a substantial body of wash water continuously in full contact with a large area of the upper foraminous belt.
- 35 horizontally spaced upper rollers for successively engaging the upper foraminous belt and correspondingly spaced rollers for engaging the lower belt and coacting with said upper rollers, respectively, to successively subject all areas of the moving board to heavy pressure, and means intermediate, and supported by, said spaced upper rollers for maintaining a substantial body of wash water continuously in full contact with a large area of the upper foraminous belt.
- 40 for applying suction to the lower foraminous belt, said last mentioned means underlying the first mentioned means and also an arear of the lower belt immediately preceding the pass between the second pair of coacting pressure rollers.
- 45

EDWARD T. STREET.
